F. D. SHEPHERD,
INTERNAL COMBUSTION ENGINE,
APPLICATION FILED FEB. 28, 1918.

1,276,583.

Patented Aug. 20, 1918.

UNITED STATES PATENT OFFICE.

FRANK D. SHEPHERD, OF SALT LAKE CITY, UTAH.

INTERNAL-COMBUSTION ENGINE.

1,276,583.

Specification of Letters Patent. Patented Aug. 20, 1918.

Application filed February 23, 1918. Serial No. 219,693.

To all whom it may concern:

Be it known that I, FRANK D. SHEPHERD, of Salt Lake City, in the county of Salt Lake, and in the State of Utah, have invented 5 a certain new and useful Improvement in Internal-Combustion Engines, and do hereby declare that the following is a full, clear, and exact description thereof.

My invention relates to internal combustion 10 engines and my object is to provide in an advantageous associated form, a spark plug, or a priming cock, or both, and the container for the spring of the engine puppet valve, and for the attainment of my 15 object, my invention consists in the structure and the parts thereof constructed and arranged, substantially as hereinafter specified and claimed.

In the accompanying drawings, I illustrate 20 several forms in which my invention may be embodied, and in such drawings:

Figure 1 is a vertical section of a combined spring container and guide of a puppet valve, and spark plug;

Fig. 2 is a bottom plan view thereof;

Fig. 3 is a detail view in side elevation, with a portion broken away of the spark plug shown in Figs. 1 and 2;

Fig. 4 is a vertical section similar to Fig. 30 1, showing a different form of spark plug and a primer cock;

Fig. 5 is a like view showing yet another form of my invention.

In my Patents No. 1,240,378 issued September 18, 1917, and No. 1,252,501 issued January 8, 1918, and in numerous pending applications, are disclosed certain improvements in puppet valves, in which the valve seating means comprises a shell or container 40 for the seating spring that is secured or attached to the cylinder head to one side of the cylinder, and with some styles of engine it is impossible with my puppet valve construction, except at great expense, to place 45 the spark plug at the center of the cylinder. By associating the spark plug with said shell or container, as in accordance with my present invention, the application of my puppet valve to the old style engines may be very 50 cheaply made, and without any change in the engine head in any respect, and while the advantageous center fire is not available, yet I am able to apply the spark plug to great advantage as to efficiency in its eccentric 55 location, and when the advantages of full utilization of the fuel that comes from

the use of my puppet valve are taken into account, it will be found that my present invention gives highly superior results.

With the construction of the cylinder 10, 60 its head 11, and the mechanism for lifting the puppet valve 12 off its seat, my invention is not concerned and in these respects the construction may be anything desired. The valve 12 is yieldingly held to its seat and returned there when lifted, by a stem 13 on its upper side that passes across the port 14, and through a guide hole in the inner end of a shell or container 15 which has a threaded end 16 that is screwed into a hole 65 70 in the cylinder head. The outer end of the stem reaches into the shell chamber 17 where it has a head 130 against which one end of the spring 150 bears, the other end of the spring bearing against the outer end, or 75 cover 160. The container, and the spring device may have any of the various forms of my patents and applications mentioned before; or any other forms, so that it will be understood that what I show in the drawings is merely illustrative and not restrictive of my invention.

In that portion of the shell or container around the central hole which forms the guide for the valve stem 13, I provide preferably a plurality of chambers that reach from the inner end of the shell quite close to the bottom of the spring chamber 17, and in one of these chambers I may mount a spark plug, and in another a priming cock 85 90 so that there may be thus assembled as one unit, the container and valve stem guide, the spark plug and priming cock.

Referring to what is shown in Figs. 1, 2 and 3, the chambers 18 around the valve 95 stem guide hole are larger in diameter for substantially half their length from their inner end outward so that an annular shoulder 19 is formed at mid length, and in one of said chambers 18 is mounted the 100 spark plug, the main body portion 20 of which is cylindrical in form and has intermediate its ends a collar or enlargement 21 which loosely fits the enlarged portion of the chamber 18, and at one end engages a 105 gasket 22 that is seated against the shoulder 19 thus making a gas-tight joint at that point and at the other end is engaged by a similar gasket 23 which is pressed against said collar 21 by a threaded thimble or bushing 24 which is screwed into the inner end of the chamber and thus the spark plug 110

body 20 is securely held in place in the chamber 18 and with gas-tight joints, which of course, is important to prevent the escape of gas past the spark plug. The bushing or thimble 24 has in its end notches 25 for the application of a suitable turning tool for screwing and unscrewing. The spark plug body 20 is of insulating material in which is embedded the wire 26 which forms one terminal or electrode of the spark plug, a portion of the wire extending beyond the inner end of the body 20, the other electrode 27 being attached to the inner end of the thimble or bushing 24, and, of course, separated from the extremity of the wire 26 the desired distance to cause the current to jump and make the igniting spark. I show two electrodes 27 secured to the bushing 24. Extending laterally from the spark plug body 20 near its outer end is a short wire 28 of conducting material which is concentric with a lateral hole 29 that leads from the exterior of the shell or container 15 into the outer end of the chamber 18 and the inner end of said wire 28 is embedded in the insulating material of the spark plug body 20, and it is mechanically and electrically connected with the wire 26 by means of an eye through which said wire 28 passes. The hole 29 is the socket for a snap plug 30 which forms the terminal of one of the conducting wires 31 that is connected with a magnetic or other source of electricity, said snap plug when inserted in the socket 29 electrically contacting with the wire 28 and being securely yet detachably held in the plug by a bead 32 on its exterior that interlocks in an annular groove 33 in the wall of the socket.

It will be observed that the spark plug is mounted as near as possible to the side of the shell or container 15 and hence its electrodes may be situated as near as possible in the port 14 to the cylinder so as to have the spark produced as near as possible to the cylinder, and one of my reasons for providing a plurality of chambers 18 is to enable the location of the spark plug as nearly as possible to the cylinder. The spark plug is placed in that chamber 18, which after the container 15 is screwed into its opening in the cylinder head is nearest the cylinder, and for convenience in locating that chamber 18, a suitable mark is made upon the shell 15 after the latter without the spark plug has been screwed into its hole in the head so that upon the removal of the shell 15, the spark plug can be placed in the chamber 18 thus identified by the mark.

Those of the chambers 18 which are not occupied by a spark plug or a priming cock are closed at their inner end each by a snap plug 34 which has a gas-tight fit and which preferably is made hollow in order not to

add weight and thus detract from another of the purposes of the chambers 18 which is to lighten the structure.

In Fig. 4 one of the chambers is shown as provided with a priming cock 35 and another chamber with a spark plug. The chambers 180 shown in Fig. 4 are of uniform diameter throughout their length and the lateral hole 290 at its outer end is inclined upward and outward and screw-threaded to receive the threaded portion of the spark plug in one case, and of the priming cock 35 in the other case, a gas-tight joint being provided in each case by a gasket 36 which is clamped between an outer surface adjacent the hole 290 and overlapping a surface on the priming cock or the spark plug as the case may be.

The body 200 of the spark plug shown in Fig. 4, of insulating material in which is embedded the wire 260 that constitutes one electrode, is substantially L-shaped so that it may be inserted through the opening 290 and then down into the chamber 180 and at its inner end it enters a thimble or bushing 240 which is screwed into the inner end of the chamber 180 and between which and the end of said body 200 is interposed a gasket 280 to make a gas-tight joint, a portion of the wire 26 projecting into the port 14 adjacent the other electrode 270 which is secured to the shell or container 15. After the body 200 with the electrode forming wire 260 has been inserted and secured at its inner end as described, a nut 300 is slipped over the portion of the body 200 which protrudes on the outside of the shell 15 and it is screwed into the hole or socket 290 and next a nut 37 is slipped over such projecting portion of the spark plug body 200 and screwed into the bushing 280 and against a shoulder on the body 200, a gasket being provided between such shoulder and the nut 37 to make a gas-tight joint. The outer end of the wire 260 is threaded to constitute the usual binding post for attaching the terminal of one of the circuit wires.

Of course, the threaded holes or sockets 290 may be formed at right angles instead of at the incline shown in Fig. 4, although the inclined arrangement is preferred because the parts are more convenient to get at.

To enable the use of spark plugs and priming cocks already on the market and without any special adaptation of the construction thereof, such as I illustrate in Figs. 1 and 4, the construction and arrangement shown in Fig. 5 may be employed where the spark plug 38 and the priming cock 39 are of a construction on the market and commonly in use. In this case the chambers 40 corresponding to the chambers 18 and 180 shown in Figs. 1 and 4 are sufficiently large at their outer portions as to admit of the ready insertion of the spark plug 38 and the

priming cock 39 and the screwing of each of the same into engagement with the intermediate threaded portion 41 of the chamber, and the desired gas-tight joint being provided by a gasket 42 between a shoulder on the spark plug or the priming cock, as the case may be, and a contiguous shoulder in the chamber 40. The construction illustrated in Fig. 5 is ordinarily available only 10 with extra large engines that have large valves, and therefore, correspondingly large spring containers or shells 15.

Having thus described my invention what I claim is:

- 15 1. As an improvement in internal combustion engines, a spring container for a puppet valve having a valve stem guide opening, and a chamber or chambers eccentric to the valve stem opening, and opening 20 into the valve controlled port.
2. As an improvement in internal combustion engines, a spring container for a puppet valve having a valve stem guide opening, a chamber eccentric to the valve stem guide opening and opening into the valve controlled port, and an ignition device 25 situated in said chamber.
3. As an improvement in internal combustion engines, a spring container for a puppet valve having a valve stem guide opening, a chamber eccentric to the valve stem guide opening and opening into the valve controlled port, and a priming cock 30 connected with said chamber.
- 35 4. As an improvement in internal com-

bustion engines, a spring container for a puppet valve having a valve stem guide opening, a chamber eccentric to the valve stem guide opening and opening into the valve controlled port, an ignition device situated in said chamber, and a priming cock connected with a second eccentric chamber opening into the valve controlled port. 40

5. As an improvement in internal combustion engines, a spring container for a puppet valve having a valve stem guide opening, and a plurality of chambers concentric with the valve stem guide opening and each opening into the valve controlled port and adapted to receive a spark plug. 45

6. As an improvement in internal combustion engines, a spring container for a puppet valve having a valve stem guide opening, a plurality of chambers concentric with the valve stem guide opening and each 50 opening into the valve controlled port and adapted to receive a spark plug, and a spark plug in one of said chambers. 55

7. As an improvement in internal combustion engines, a spring container for a puppet valve having a valve stem guide opening, a plurality of chambers concentric with the valve stem guide opening and each opening into the valve controlled port and adapted to receive a spark plug, a spark plug 60 in one of said chambers, and filling plugs in other of said chambers. 65

In testimony that I claim the foregoing I have hereunto set my hand.

FRANK D. SHEPHERD.
